[57] CLAIM

The ornamental design for a combined cigarette lighter and base therefor, as shown and described.

DESCRIPTION

FIG. 1 is a perspective view of a combined cigarette lighter and base therefor showing my new design; FIG. 2 is a top plan view of the base only; FIG. 3 is a side elevational view thereof with the opposite sides being mirror images thereof; FIG. 4 is a bottom plan view thereof; FIG. 5 is a top plan view of a second embodiment of the design shown in FIG. 1 with the lighter removed; FIG. 6 is a side elevational view thereof with the opposite sides being mirror images thereof; FIG. 7 is a bottom plan view thereof; FIG. 8 is a top plan view of a third embodiment of the design shown in FIG. 1 with the lighter removed; FIG. 9 is a side elevational view thereof with the opposite sides being mirror images thereof; FIG. 10 is a bottom plan view thereof; FIG. 11 is a top plan view of a fourth embodiment of the design shown in FIG. 1 with the lighter removed; FIG. 12 is a front elevational view thereof with the rear being a mirror image thereof; FIG. 13 is a side elevational view thereof with the opposite side being a mirror image thereof; FIG. 14 is a bottom plan view thereof; FIG. 15 is a top plan view of a fifth embodiment of the design shown in FIG. 1 with the lighter removed; FIG. 16 is a front elevational view thereof; FIG. 17 is a side elevational view thereof with the opposite side and rear views being mirror images thereof; FIG. 18 is a bottom plan view thereof; FIG. 19 is a side elevational view of the first embodiment with the opposite side being a mirror image thereof; FIG. 20 is an end elevational view thereof; FIG. 21 is an opposite end elevational view thereof; and, FIG. 22 is a top plan view thereof.

The lighter has been omitted in FIGS. 2-18 for ease of illustration.

The surface shading shown in FIGS. 4, 7, 10, 14 and 18 represents a gray bottom surface.
